Application filed October 14, 1893. Serial No. 488,177. Term of patent 3½ years.

To all whom it may concern:

Be it known that I, CHARLES BOOZE, a citizen of the United States, residing at Buffalo, in the county of Erie and State of New York, 5 have invented and produced a new and original Design for Wall-Paper, of which the following is a specification.

The design consists of an arrangement of flowers and leaves of the lily of the valley 10 with sprays of grass placed with said flowers as represented in the accompanying drawing. These flowers and leaves and sprays of grass are arranged in bunches or groups at suitable 15 distances apart over the surface of the paper as shown. The border or upper portion of the design is also formed of these flowers and

leaves of the lily of the valley with sprays of grass arranged in a wavy horizontal manner forming a continuous border as shown, with an ornamental band separating the border 20 from the hanging.

What I claim is—

1. The design for wall paper herein shown and described.
2. In the design for wall paper, the border 25 herein shown and described.

Witness my hand this 10th day of October, 1893.

CHARLES BOOZE.
